UNITED STATES PATENT OFFICE.

PETER ANDERSON WILKIE, OF WELLINGTON, NEW ZEALAND.

DESIGN FOR A TOY DART.

Application filed August 15, 1924. Serial No. 10,466. Term of patent 7 years.

To all whom it may concern:

Be it known that I, PETER ANDERSON and WILKIE, a subject of the King of England, residing at Wellington, in the Dominion of New Zealand, have invented a new, original, and ornamental Design for a Toy Dart, of which the following is a specification, reference being had to accompanying drawings, forming a part thereof.

Fig. I is a front elevation of my design,

Fig. II is an end view of the same.

I claim:—

The ornamental design for a toy dart substantially as shown.

PETER ANDERSON WILKIE.
